UNITED STATES PATENT OFFICE

99,335

DESIGN FOR A COAT

Julius Leiterman, New York, N. Y.

Application March 20, 1936, Serial No. 61,703

Term of patent 3½ years

To all whom it may concern:

Be it known that I, Julius Leiterman, a citizen of the United States of America, residing in Manhattan, county of New York and State of New York, have invented a new, original, and ornamental Design for a Coat, of which the following is a specification, reference being had to the accompanying drawing, forming part thereof, wherein,

Figure 1 is a front view of a coat showing my new design.

Figure 2 is a rear view of the coat shown in Figure 1.

The lines extending from the armhole seams represent pleats.

The shaded area above the insert on the rear portion of the sleeve represents surplus material.

I claim:

The ornamental design for a coat, substantially as shown, and described.

JULIUS LEITERMAN.
